[57] CLAIM

The ornamental design for a combined table and recessed storage unit, as shown.

DESCRIPTION

FIG. 1 is a front perspective view of a combined table and recessed storage unit showing my new design;
FIG. 2 is a front perspective view with the storage door in operative position;
FIG. 3 is a front elevational view taken from FIG. 1;
FIG. 4 is a sectional view taken along lines 4—4 of FIG. 3;
FIG. 5 is a rear elevational view thereof;
FIG. 6 is a side elevational view thereof; the opposite side being a mirror image thereof;
FIG. 7 is a top plan view thereof; and
FIG. 8 is a bottom plan view thereof.
